UNITED STATES PATENT OFFICE.

HENRY A. ADAMS, OF SANDWICH, ILLINOIS.

HAY-RAKE.

SPECIFICATION forming part of Letters Patent No. 749,711, dated January 19, 1904.

Application filed August 18, 1903. Serial No. 169,873. (No model.)

To all whom it may concern:

Be it known that I, HENRY A. ADAMS, a citizen of the United States, and a resident of Sandwich, county of Dekalb, and State of Illinois, have invented certain new and useful Improvements in Hay-Rakes, of which the following is a specification and which are illustrated in the accompanying drawings, forming a part thereof.

10 The invention relates to that type of hay-rakes particularly adapted for side delivery, in which a plurality of rake-heads are mounted so as to revolve about a center, but are prevented from rotation.

15 The object of the invention is to provide, in a machine of this type in which the rake-head is provided with a pivot-shaft parallel but not coincident with itself, a suitable brace intermediate of the ends of the rake-head to prevent it from bowing out under the influence of centrifugal or other pressure.

The invention consists in the structure herein described and claimed, and illustrated in the accompanying drawings, in which—

25 Figure 1 is a detail vertical longitudinal section of the rake-frame, and Fig. 2 is a detail transverse section thereof. Fig. 3 is a sectional detail of one of the parts of the machine.

I have not deemed it necessary to illustrate 30 the rake in full, but show only those parts to which the invention particularly applies.

At 10 is shown one of the beams for carrying the rake-frame, and at 11 the shaft thereof, which is provided with a pinion 12, by means 35 of which it may be rotated. Cross-arms 13 are fixed upon the shaft 11, and at their ends are journaled pivot-rods 14 15, attached to the rake-heads 16 17 by means of clips, as 18.

The rake-teeth 20 are set in the heads 16 17 40 and secured to the pivot-shafts 14 15, preferably by simply twisting them around the same.

The rake-heads are prevented from rotation by any suitable means, as shown by a sprocket-chain 21, engaging a sprocket-wheel 22, fixed 45 to the journal-box 23 of the shaft 11, this chain turning over sprocket-wheels 24 25, fixed upon the ends of the pivot-shafts 14 15, respectively.

The mechanism thus far described is old and is shown in Letters Patent No. 722,931, granted to me on the 17th day of March, 1903.

The novel feature of the machine resides in means for bracing the rake-heads intermediate of their ends. To this end there is applied to each rake-head a plate 26, radially apertured to receive the shafts 14 15 and the heads 16 17. 55 From the disk face of each of these plates there projects a flange 27, which is concentric with the shaft 14 or 15. The radial apertures of the plates 26 are flanked by flanges 19, which are bolted to the heads 16 17, and the heads 16 60 17 fitting thereon, so as to be eccentric as to the heads and concentric as to the shafts. Each of the flanges 27 is encircled by a strap, and the two straps are united. In order to secure cheapness of construction and simplicity of assembling, I prefer to give the straps 28 29 substantially a U shape, their ends being sufficiently prolonged so as to overlap and being united by means of bolts 30 and 31, located, respectively, upon opposite sides of and 70 adjacent to the shaft 11. As the rake-frame revolves the straps 28 29 slide upon the peripheral faces of the flanges 27, so as to provide entire freedom of movement and effectively bracing the rake-heads against outward 75 bowing, thereby preventing them from interfering with other parts of the frame of the machine, while permitting them to be of lighter construction than when not thus braced.

I claim as my invention—

1. In a hay-rake, in combination, a rotatable shaft, cross-arms fixed to the shaft, a pair of rake-heads, a pivot-shaft attached to each head and journaled in the cross-arms, means for turning the pivot-shafts relatively as to 85 the first-named shaft, a plate mounted upon each rake-head and having a peripheral face concentric with the pivot-shaft attached thereto, and a strap encircling the two plates.

2. In a hay-rake, in combination, a rotatable shaft, cross-arms fixed to the shaft, a pair of rake-heads, a pivot-shaft attached to each head and journaled in the cross-arms, means for turning the pivot-shafts relatively as to the first-named shaft, a radially-recessed plate 95 mounted upon each rake-head and being concentric with the pivot-shaft attached thereto, and a strap encircling the two plates.

3. In a hay-rake, in combination, a rotatable shaft, cross-arms fixed to the shaft, a pair 100

of rake-heads, a pivot-shaft attached to each head and journaled in the cross-arms, means for turning the pivot-shafts relatively as to the first-named shaft, a plate mounted upon each rake-head and being concentric with the pivot-shaft attached thereto, and a strap comprising two U-shaped members each fitted to

one of the plates and having their ends secured together.

HENRY A. ADAMS.
